UNITED STATES PATENT OFFICE

HERMANN LEMP, OF GLEN ROCK, NEW JERSEY, ASSIGNOR TO INGERSOLL-RAND COMPANY, OF JERSEY CITY, NEW JERSEY, A CORPORATION OF NEW JERSEY

SPEED CONTROL APPARATUS FOR LOCOMOTIVES

Application filed July 17, 1930. Serial No. 468,525.

This invention relates to speed control apparatus, but more particularly to apparatus of this character adapted for use on the prime mover, as for instance, an internal combustion engine, of a locomotive.

One object of the invention is to enable the power controlling means of the engine to be conveniently actuated for accelerating and decelerating the speed of the engine and to 10 remain in the various positions which the power controlling means may assume without being hindered in its movements or disturbed in its various power controlling positions by any relative displacement between 15 the engine and the various portions of the locomotive or vehicle whereon the engine and the control apparatus are mounted.

Another object of the invention is to enable the power controlling means to be actuated by suitable pneumatically operated devices which themselves may be controlled by either one of a plurality of control devices which may be located remotely from both the engine and the said pneumatic devices.

25 A further object is to enable the supply of power or fuel to a plurality of dis-associated and relatively remotely located engines supported either on a single locomotive or on a plurality of locomotives to be controlled 30 from either one of a plurality of control stations located on each locomotive.

Other objects are to assure synchronized 35 operation of a plurality of engines remotely located with respect to each other, to obviate the possibility of operating the engines at critical speeds for prolonged periods of time, and to afford a flexible and simplified speed controlling apparatus which will be 40 efficient in operation and inexpensive to maintain.

Other objects will be in part obvious and in part pointed out hereinafter.

In the accompanying drawings illustrating 45 the invention and in which similar reference characters refer to similar parts,

Figure 1 is a plan view of a plurality of locomotives connected to operate in unison and having the invention applied thereto, and

Figure 2 is a diagrammatic view, partly in section, of a controlling apparatus.

Referring more particularly to the drawings and at first to Figure 1, A and B designate locomotives connected in this instance 55 by suitable coupling devices C. The locomotives A and B may be substantially identical in all their essential respects and it is therefore considered necessary to describe only one locomotive together with its auxiliary 60 devices.

The prime mover of the locomotive A may comprise as illustrated, an internal combustion engine D connected to drive the generator E from which lead cables F to a main 65 motor G intended to propel the locomotive. The main motor G may be connected to the driving axle H of the locomotive A carried in any suitable manner, as for instance, by a pinion J carried by the motor G and meshing 70 with a gear K mounted on the driving axle H and on the end of which are mounted traction wheels L.

The locomotives carry a suitable compressing unit, as for instance a compressor O, connected to an electric motor P whereby the 75 said compressor O is driven. The motor P, like the main motor G, may also be suitably connected to the generator E as by means of conductors Q.

The compressor O is provided with a suitable discharge pipe R for conveying compressed fluid, such as air, to a storage receiver S carried by the locomotive, and from the storage receiver S leads a supply pipe T which is connected to a main supply or service pipe U extending longitudinally of the locomotive and carrying at its extremities flexible conduits or hose couplings V of any well known type adapted to establish 85 communication between the service lines of adjacent locomotives or trains of cars to which the locomotive may be connected. The supply or service line U may, as is customary, 90 serve as the main conduit for supplying pressure fluid to the various pneumatically actuated devices wherewith locomotives are usually equipped.

For simplicity of illustration, the engine 100 D is shown as being equipped with fuel con-

trolling apparatus in the form of a carburetor *W* to which the fuel may be conveyed from a suitable source of supply by a connection *X*. The carburetor *W* is accordingly provided with the usual choke or throttle valve *Y* for controlling the admission of air to the various combustion chambers of the engine and thus also, in accordance with the well understood principle, the supply of fuel to the combustion chambers.

As is well known, one difficulty frequently encountered in attempts at close regulation of the fuel supply to an internal combustion engine used as a prime mover for locomotives is that of maintaining the power or fuel controlling device, such as the throttle valve *Y*, in substantially fixed position during the running period of the locomotive. This is particularly the case where mechanical connections are employed for transmitting the movement of the manually operable devices, such as a control lever, to the throttle valve *Y* of the carburetor, and more particularly during the time that the locomotive is in motion. It is during such times that, owing to irregularities in the track upon which the locomotive runs, the platform or floor upon which the engine and the different controlling apparatuses are mounted is distorted thus causing the engine and the controlling apparatus to shift their positions somewhat with respect to each other. Obviously when mechanical means are used for transmitting the motion of controlling devices to the throttle valve *Y* any condition which may serve to shift the position of the controlling device will, in consequence affect the position of the throttle valve *Y* and therefore the speed of the engine *D*.

According to the present invention it is contemplated to provide apparatus of extreme simplicity for controlling the throttle valve *Y* in such manner that, irrespective of any distortion of the floor of a locomotive, the throttle valve *Y* or any equivalent fuel or power controlling means may remain unaffected and thus insure against an involuntary departure from the desired speed of the engine *D*. A preferred form of the means provided to bring about this result comprises a cylinder *Z* having a plunger *b* therein which is pivotally connected, as by means of a rod *c*, to a suitable lever *d* which may be fixedly secured to the throttle valve *Y*. Preferably the plunger *b* is provided with a reduced portion *e* of larger diameter than the rod *c*, and to the free end *f* of which the said rod *c* may be connected.

Disposed within the cylinder *Z* and encircling the reduced portion *e* is a calibrated spring *g* which acts against the end of the plunger *b* to oppose the movement of the plunger in the direction for increasing the fuel supply of the engine *D*. The opposite or rear end of the plunger *b* in this instance

constitutes a pressure surface *h* against which pressure fluid may be directed for actuating the throttle valve *Y* to its various fuel controlling positions for accelerating the speed of the engine *D*.

The pressure fluid utilized for actuating the plunger *b* is conveyed thereto from the service line *U* by a conduit *j* which may be provided with suitable branches *k* and *o* to connect the conduit *j* with the service line *U*. The points of juncture of the branches *k* and *o* with the service line *U* are preferably near the extremities of the locomotive and at which points are preferably located suitable manual control stations designated generally by *p*, the said control stations being interposed in this instance in the branches *k* and *o* to control communication between the service line *U* and the conduit *j*.

The conduit *j* extends along the length of the locomotive and is provided at its ends with flexible hose couplings *r* to connect to similar couplings *r* carried by a conduit *j* of the adjoining locomotive *B*. The conduit *j* is provided with a branch pipe *s* which is connected to the cylinder *Z* for supplying pressure fluid thereto to actuate the plunger *b*.

To the end that the pressure fluid for actuating the plunger *b* may be admitted into the cylinder *Z* in a simplified manner contemplated to eliminate the necessity of a multiplicity of settings of the manually operable means whereby the admission of fluid is controlled to the cylinder *Z*, such manually operable means are in the form of control valves *t* forming the control stations *p* and encased by valve chests *u* to which the branches *k* and *o* and the service line *U* are connected. The control valves *t* are of the rotary type and are shown as having central chambers *v* which may be in constant communication with the service line *U*. In the walls of the control valves *t* are ports *w* which are adapted to register with the branches *k* and *o* for admitting pressure fluid to the cylinder *Z*.

In the peripheral surfaces of the control valves *t*, and preferably in the same transverse planes as the ports *w*, are partly annular grooves *x* which are adapted to establish communication between the branch pipes *k* and *o* and exhaust ports *y* in the casings *u*. On the peripheral surfaces of the control valves *t* and between the grooves *x* and the ports *w* are plain unbroken portions *z* which, when overlying the inlet openings of the branch pipes *k* and *o*, serve to seal said branch pipes and thus entrap any pressure fluid in the cylinder *Z* and the conduits leading thereto which may have been previously admitted to these elements by the ports *w* in the control valves *t*.

Means are provided for automatically augmenting the pressure fluid acting against the plunger *b*, whenever the pressure in the cylinder *Z* exceeds a predetermined amount.

der Z has reached a predetermined value at which it would move the plunger b and therefore the throttle valve Y into a position corresponding to the critical speed range of the engine D. The means provided for this purpose comprises a valve casing 2 having a valve chamber 3 therein to accommodate a reciprocatory valve 4. In the casing 2 is a port 5 to which pressure fluid is supplied by a pipe 6 connected to the service line U.

The port 5 is intended to be controlled by the valve 4 and said valve is provided with a transverse port 7 which is adapted to register with the port 5. The valve 4 is further provided with a longitudinally extending port 8 which opens from the end of the valve and communicates with the transverse port 7. Connected to one end of the casing 2 is a pipe 9 which is preferably connected with its other end to the conduit j.

In order to normally hold the valve 4 in a position to prevent communication between the ports 5 and 7 a spring 10 is disposed in the casing 2 to bear against one end of the valve 4. The spring 10 is calibrated to yield to a certain predetermined pressure to which the valve 4 may be exposed in order to permit the valve to be shifted to a position wherein communication between the ports 5 and 7 may be established. The spring 10 is however preferably provided with means for varying the tension thereon, and to this end said spring is provided with an adjustable valve seat 11 disposed in the casing 2 and adapted to be shifted or adjusted by a regulating screw 12 threaded in the end of the casing 2.

The operation of the apparatus is as follows: Let it be assumed that the service lines U and the conduits j of the several locomotives A and B are in communication in the manner illustrated in Figure 1 and that the plunger b and the valve 4 occupy the positions shown in Figure 2. In these positions of the parts the throttle valves Y of the carburetors W which control the fuel admission to the several engines D will occupy positions to operate said engines D at what may be termed the idling speeds. The plungers b will then be held in retracted positions by the springs g acting thereagainst.

If then it be intended to accelerate the speed of the engines D all but one of the control valves t may be set in such positions that the blank or unbroken portions z of the control valves t will overlie the respective branch, either o or k which they are intended to control. The remaining control valve t is then rotated to place its port w in registry with the branch associated therewith, as for instance, the branch k.

With the control valve t in this position pressure fluid will flow through the conduit j and into the cylinders Z to actuate the plungers b associated with each carburetor in

a direction for increasing the fuel supply to the engines D. This, as will readily be observed, requires only one pressure admission position for the control valve, irrespective of the speed at which it may be desired to operate the engines, it being merely necessary to maintain the control valve t in this position until each throttle valve Y has been shifted to a position to assure the desired speed of the engines D.

After the required speed has been attained the control valve t is shifted to what may be termed the intermediate position of the control valve, that is, to a position in which the unbroken portion z overlies the inlet end of the branch which it controls. The pressure fluid admitted into the cylinders Z and the conduits connecting the said cylinders with the control valve will then be entrapped therein. In consequence, the throttle valve Y will remain fixedly in the required positions for maintaining uniform speed of the engines. Inasmuch that all the plungers b are exposed to pressure fluid of identically the same value on one end and on the other end to spring pressures of the same value it follows that each plunger b will have been moved and will be held in identically the same position and that therefore the throttle valves Y of each carburetor will also occupy corresponding positions.

Whenever it is desired to operate the engines D at maximum speed the control valve t is placed in a position to assure constant communication between the chamber v and the cylinders Z. In this position of the control valve t sufficient pressure fluid will be admitted to the conduit j and to the cylinders Z to actuate the plungers b throughout their entire range of travel so that the free ends f thereof may abut the ends of the cylinders Z. In these positions of the plungers b the throttle valves Y will occupy positions in which maximum fuel admission to the engines D will be assured and the engines D will then operate at maximum speed.

Whenever the exigencies of the work require a reduction in speed, the control valve t may be moved into a position in which its annular groove x will establish communication between the branch pipe k and the exhaust port y to bleed a portion of the pressure fluid from the cylinders Z or, if it be desired to reduce the speed of the engines to idling speeds, the control valve t may remain in this position and in which case the pressure surfaces h of the plungers b are exposed only to atmospheric pressure.

From the foregoing it will be readily apparent that the control valve has only three positions, namely, two limiting positions and an intermediate position for actuating the plungers b and the throttle valves Y of the carburetors W to an infinite variety of positions and for maintaining these elements in

such positions unaffected by any relative displacement between the several controlling devices incident to distortion of the support or platform whereon they are mounted. In other words, to accelerate the speed of the engines it is merely necessary to rotate the control valve *t* to one limiting position in which its port *w* registers with the adjacent branch of the conduit *j*.

The position of the plungers *b* and consequently the speed at which the engines *D* will thereafter operate depends entirely upon the length of time that the control valve *t* is held in this position. After the desired speed of the engines has been reached the control valve may be moved to an intermediate position in which the unbroken portion *z* of the control valve will seal the conduit *j*. To decrease the speed of the engines or to reduce such speed to an idling speed the control valve *t* may be moved to another limiting position in which position the pressure fluid will be exhausted from the cylinders *Z* so that the springs *g* may act to restore the throttle valves *Y* to the idling positions.

The manner in which the valve 4 operates to avoid the prolonged operation of the engines *D* at critical speeds is as follows: Let it be assumed that the value of the pressure 30 acting against the plungers *b* to move the throttle valves *Y* to positions in which the engines *D* will operate at the critical speed is, say, fifty pounds. If then the spring 10 be adjusted to yield at a slightly lower pressure, as for instance forty-nine pounds, the pressure fluid flowing through the pipe 9 and acting against the end of the valve 4 will 35 actuate the valve 4 in the direction of the spring 10.

During a portion of this movement of the valve 4 the port 7 in the valve will register with the port 5 and pressure fluid will then flow directly from the service line *U* into the valve chamber 3, thence into the conduit *j* and into the cylinders *Z*. The pressure fluid thus admitted by the valve 4 will augment the pressure acting against the plungers *b* to bring the pressure in the cylinders *Z* to such a value that the plungers *b* will be quickly shifted and cause the engines *D* to operate at a speed slightly in excess of what may be said to be the critical speed.

Upon the operation of the valve 4 in the manner described and the consequent increase in pressure in the cylinders *Z*, the valve 4 will remain in the retracted position as long as the pressure in the cylinders *Z* remains dominant over that exerted by the spring 10. Upon moving the control valve *t* to a position for exhausting the pressure fluid from the cylinders *Z* the port 7 in the valve 4 again moves across the port 5 in the casing 2. Obviously there will then be an additional charge of pressure fluid from the service line into the conduit *j*. This newly admitted

pressure fluid, however, will not be effective to disturb either the positions of the plungers *b* or to interfere with their retractive movement since then the conduit *j* is in communication with the atmosphere.

In practice the present invention has been found to be exceedingly efficient. As will be readily apparent, it affords a simplified means of controlling the power supply of a plurality of engines mounted either upon 70 separate supports of the same locomotive or upon different locomotives. It affords the utmost flexibility in the operation of the several controlling devices, however remotely located from the control station, and assures the operation of a plurality of disassociated engines in synchronism. Moreover, by reducing the control positions of the control valves *t* to three in number an apparatus is provided whereby the operator of the locomotive is not required to set the control valve to a multiplicity of intermediate controlling positions in which each intermediate position is intended to be an indication of the speed 80 of the engine.

The present device enables the operator to judge the performance of the engine entirely by the speed of the locomotive in somewhat the same manner as an operator of an automobile regulates the speed of his engine 95 as based upon the speed of the automobile or upon the varying conditions of the surface over which it travels.

I claim:

1. In a control apparatus for locomotives, 100 the combination of an internal combustion engine and means for controlling the supply of fuel to the engine, a source of pressure fluid including a supply line, pressure-responsive means for actuating the first mentioned means, means for controlling the flow of pressure fluid directly from the supply line to the pressure-responsive means for actuating the first said means, and means for controlling the period of time for which the engine may be operated at a certain predetermined speed.

2. In a control apparatus for locomotives, the combination of an internal combustion engine and means for controlling the supply 110 of fuel to the engine, a source of pressure fluid including a supply line, pressure-responsive means for actuating the first mentioned means, manually operable means associated with the supply line and being connected to admit pressure fluid directly into the pressure-responsive means, and automatic means for limiting the period of time for which the engine may be operated at its critical speed.

3. In a control apparatus for locomotives, the combination of an internal combustion engine and means for controlling the admission of fuel thereto, a source of pressure fluid including a supply line, pressure-responsive 120 means for actuating the first mentioned means, and automatic means for admitting pressure fluid directly into the pressure-responsive means.

- spring-opposed means connected to actuate the first mentioned means, a control valve in the supply line to control the flow of pressure fluid to and from the pressure-responsive means, and spring-pressed valve means interposed between the supply line and the pressure-responsive means, said valve means being exposed to the same pressure as the pressure-responsive means and adapted to be opened by a predetermined pressure to augment the pressure in the pressure-responsive means, thereby accelerating the speed of the engine and thus avoiding the prolonged operation of the engine at a critical speed.
6. In a control apparatus for locomotives, the combination of an internal combustion engine and means for controlling the admission of fuel thereto, a source of pressure fluid including a supply line, pressure-responsive spring-opposed means connected to actuate the first said means, a manually operable control valve in the supply line to control the flow of pressure fluid to and from the pressure-responsive means, and an auxiliary valve automatically operative to augment the pressure in the pressure-responsive means whenever the pressure therein reaches a certain predetermined value, thereby preventing the first mentioned means from remaining stationary in a position corresponding to the critical speed range of the engine.
5. In a control apparatus for locomotives, the combination of an internal combustion engine and means for controlling the admission of fuel thereto, a source of pressure fluid including a supply line, pressure-responsive spring-opposed means connected to actuate the first said means, a manually operable control valve in the supply line to control the flow of pressure fluid to and from the pressure-responsive means, and an auxiliary valve automatically operative to augment a certain predetermined pressure in the pressure-responsive means for accelerating the movement of the first mentioned means through a fuel controlling position corresponding to the critical speed range of the engine.
6. In a control apparatus for a plurality of locomotives intended to be operated in synchronism, engines on the locomotives, individual pressure-actuated power control means on each engine, a conduit affording communication between the control means, a control valve on one locomotive associated with the conduit to simultaneously control the flow of pressure fluid to all the control means, and means to control the period of time for which the engines may be operated at a certain predetermined speed.
7. In a control apparatus for a plurality of locomotives intended to be operated in synchronism, engines on the locomotives, individual pressure-actuated power control means on each engine, a conduit affording communication between the control means, a control valve on one locomotive associated with the conduit to simultaneously control the flow of pressure fluid to and from all the control means, and means to control the period of time for which the engines may be operated at a certain predetermined speed.
8. In a control apparatus for a plurality of locomotives intended to be operated in synchronism, engines on the locomotives, individual pressure-actuated power control means on each engine, a conduit affording communication between the control means, a source of pressure supply including a supply line, a plurality of control valves on each locomotive interposed between the supply line and the conduit, either one of which control valves may serve to simultaneously control the flow of pressure fluid to and from all of the control means, and pressure actuated means to control the period of time for which the engines may be operated at a certain predetermined speed.
9. In a control apparatus for a plurality of locomotives intended to be operated in synchronism, engines on the locomotives, individual throttle valves on each engine, individual pressure-responsive spring-opposed means connected to operate the throttle valves, a conduit affording communication between the pressure-responsive means, a source of pressure fluid including a supply line, a control valve interposed between the supply line and the conduit to control the flow of pressure fluid to and from all of the pressure-responsive means, said control valve being movable to one position for simultaneously actuating the throttle valves to any fuel controlling positions and being movable to another position for entrapping pressure fluid in the pressure-responsive means to hold the throttle valves immovable in any fuel controlling position, and means to automatically augment the pressure in the pressure responsive means whenever the pressure therein reaches a predetermined value, thereby preventing the throttle valves from remaining stationary in a position corresponding to the critical speed range of the engines.
10. In a control apparatus for locomotives, an internal combustion engine, means for controlling the supply of fuel to the engine, and means for momentarily augmenting the fuel supply when the engine reaches a predetermined speed.
- In testimony whereof I have signed this specification.
- HERMANN LEMP.
